Primary Examiner — Mitchell I. Siegel

CLAIM

The ornamental design for a golf club head, as shown and described.

DESCRIPTION

FIG. 1 is a front and top perspective view of a golf club head; FIG. 2 is a rear and bottom perspective view of the golf club head of FIG. 1

FIG. 3 is a front elevational view of the golf club head of FIG. 1;

FIG. 4 is a rear elevational view of the golf club head of FIG. 1;

FIG. 5 is a top view of the golf club head of FIG. 1; FIG. 6 is a bottom view of the golf club head of FIG. 1; FIG. 7 is a left side view of the golf club head of FIG. 1; and, FIG. 8 is a right side view of the golf club head of FIG. 1. The broken lines shown on the drawings form no part of the claimed design.

1 Claim, 4 Drawing Sheets
